UNITED STATES PATENT OFFICE.

SYLVESTER A. GATES, OF DETROIT, MICHIGAN.

TAR-LAID BUILDING MATERIAL.

Application filed April 10, 1926. Serial No. 101,049.

This invention relates to tar laid building material and has special reference to blocks, bricks, slabs, tiles and other building material made from concrete or the like.

5 My invention aims to provide slabs or brick-like tiles that may be easily and quickly installed for forming a wall, partition or the like of a building or other structure. It is in this connection that the slab or brick-like 10 tile has been especially designed as part of an outer wall that may be secured to studing, siding or other structural parts of a building.

My invention further aims to provide novel 15 interlocking edge connections for superimposed slabs or brick-like tiles. In some instances the connection means is a tongue and groove connection having tar or the like as a seal in the connection, and in other instances a connection may be established by 20 metallic inserts which may also be tarred to provide an air tight connection between adjacent slabs or tiles. In other instances the slabs or tiles are prepared for the tar connection. In the grooves of a slab or tile may 25 be placed a strip of tar which may be subjected to heat, by a blow torch or other heating instrumentality to soften the tar so that the tongue or connecting part of an adjacent 30 slab or tile may be placed in the melted tar whereby the tar will seal the tongue and groove connection. With the slabs or tiles provided with the tar or sealing material the slabs or tiles are prepared for installation and 35 practically as fast as a workman may manipulate a blow torch, the slabs or tiles may be placed in superposed relation against a siding or inner wall. At suitable intervals wall 40 fasteners may be used to anchor the slabs or tiles, and there is no danger of the slabs or tiles being broken or injured by such fasteners as I employ for anchoring the composite wall.

My invention will be hereinafter specifically described and then claimed, and reference will now be had to the drawing wherein

Figure 1 is a front elevation of a portion of an outer wall composed of slabs or tiles in accordance with this invention;

50 Fig. 2 is a perspective view of a slab or tile;

Fig. 3 is a similar view of a metallic frame

adapted to form the skeleton portion of the slab or tile;

Fig. 4 is a vertical sectional view of a portion of a wall shown in Fig. 1;

Fig. 5 is a horizontal sectional view of a vertical connection between adjoining slabs or tiles;

Fig. 6 is a perspective view of a fastener or clip used in connection with the wall;

Figs. 7, 8 and 9 are detail views, on a similar scale, of a tongue and groove tile, and

Fig. 10 is a vertical sectional view of a portion of a wall formed of tiles such as shown in Figs. 7 to 9 inclusive.

Reference will first be had to Figs. 1 to 6 inclusive showing a slab or block 1 made from concrete or other cementitious material and the slab is comparatively flat and oblong in elevation. In the making of this slab a metal border frame 2 is mounted therein, said frame forming a skeleton reinforcing member for the slab and affording means of connecting one slab to another. The metallic frame comprises a longitudinal tongue bar 3, vertical groove bars or channels 5 and a longitudinal groove bar or channel 4. The ends of these bars are spot welded or otherwise connected together with the end bars 5 in substantially the same plane. This is also true of the longitudinal bars 3 and 4 and the frame is located in the slab 1 so that the groove or channel bars 4 and 5 are substantially embedded therein, while the tongue bar 3 protrudes from the slab and is adapted to extend into a complementary groove bar 4 of an adjoining slab. The groove bars 5 are adapted to confront similar groove bars of endwise adjoining slabs, so that the confronting groove bars 5, as best shown in Fig. 5, will form a vertical opening to receive a fastening member 6 having offset tongue 7. This fastening member is adapted for securing the slabs to siding 8, studs 9 or other building material forming an inner wall. The offset end 7 of each fastener member will protrude above the slabs in which it is mounted, so that the slabs will not materially interfere with the driving of a nail 10, through the offset end 7 of the fastening member 6 to secure it to the inner wall.

Since the fastening member is held in groove bars 5 of the slab frames, the cementitious material will not be broken or

fractured incident to securing the fastening members to the inner wall.

In order that the slabs may be placed in superposed relation and evenly laid, the confronting ends of the slabs, at the upper edges thereof, are provided with recesses 11 into which extend the offset ends 7 of the fastening members 6.

Before further describing the laying of this form of metal reinforced cementitious slab, reference will be had to Figs. 7 to 9 inclusive showing a slab 12 devoid of any metallic reinforcement. The slab 12 may be rectangular in elevation with tongues 13 on two of its edges and grooves 14 in the other edges of the slab, so that the slabs may be laid in superposed staggered relation with tongue and groove connections between the slabs. To secure these slabs to the inner wall, each slab has an angularly disposed nail opening 15 into which a nail may be driven to anchor each slab relative to the inner wall.

In laying either form of slab I find it advantageous to seal the tongue and groove connections wherever possible to insure a tight connection and exclude the elements. I find that tar may be advantageously used as a sealing material, therefore I lay a strip or bead of tar in each groove of a slab.

Melted or semi-liquid tar is poured in the groove to solidify therein and become an integral part of the slab, so that the tar cannot become accidentally displaced during shipment. When the slabs are ready to be laid, a blow torch or other heating instrumentality is moved along the inlaid tar to melt or place it in a semi-fluid condition that will permit of a tongue either entering the tar or spreading the tar over the wall of the groove.

When the tar solidifies there is a positive connection between tongue and groove slabs 12 as shown in Fig. 10, or tongue and groove slabs 1, as shown in Fig. 4.

As shown in Figs. 4 and 5 the metallic lined grooves of the slabs or blocks may have tar or other malleable sealing material therein and this is particularly true in connection with the vertical groove members 5

so that the fastening members 6 will be sealed between the confronting groove bars. Such a quantity of tar may be used in each groove bar that it will be displaced by the fastening and form a bond between the confronting ends of the slabs or blocks.

From the foregoing it will be observed that there is a method involved in my invention, which method consists in placing sealing material in grooved building material to solidify therein; then welding the solidified sealing material to place in a fluid or semi-fluid condition, and then placing the tongue building material on the groove building material with the tongues in the grooves so that the sealing material when again solidified will seal the tongue and groove building material. The method is carried into effect by using specially prepared building material and a tar inlaid slab or block constitutes an article of manufacture, with or without the metallic reinforcement.

It is thought that the utility of my invention will be apparent without further description, and while in the drawing there are illustrated the preferred embodiments of my invention, it is to be understood that the structural elements are susceptible to such variations and modifications as fall within the scope of the appended claims.

What I claim is:

1. A method of laying tongue and groove building slabs having in the grooves thereof a fusible material which is hard at ordinary temperatures, consisting in melting said material and inserting therein the tongues of adjacent slabs.

2. A building slab having tongues at certain edges and grooves at other edges thereof, said grooves containing a fusible material which is hard at ordinary temperatures.

3. A slab having tongues inserted in certain edges and channel members in other edges thereof, said channel members containing a fusible material which is hard at ordinary temperatures.

In testimony whereof I affix my signature.

SYLVESTER A. GATES.
